UNITED STATES PATENT OFFICE.

WERTER C. HIGGINS, OF NORWICH, CONNECTICUT.

STEAM AND HOT-WATER GENERATOR.

SPECIFICATION forming part of Letters Patent No. 434,928, dated August 26, 1890.

Application filed May 12, 1890. Serial No. 351,497. (No model.)

To all whom it may concern:

Be it known that I, WERTER C. HIGGINS, a citizen of the United States, residing at Norwich, in the county of New London and State 5 of Connecticut, have invented certain new and useful Improvements in Steam and Hot-Water Generators, which improvements are fully set forth and described in the following specification, reference being had to the accompanying three sheets of drawings.

The immediate object of my invention is to cut up the water-space in steam or hot-water generators and bring the water into such near relation to the fire that the products of combustion may be utilized to the greatest possible extent, keeping in view meanwhile that such result should be reached cheaply and the construction be such as not to interfere with the free circulation of water in hot-water heaters. With these desiderata in view I have provided a novel vessel, forming a part 15 of the boiler-section, located within the fire-pot, with pipes or passages connecting said vessel with said boiler at several points.

25 The annexed drawings illustrate clearly my said invention, Figure 1 being a front side elevation of a hot-water generator embodying my improvements, and Fig. 2 a central vertical sectional view of the same on line $z z$ of Fig. 1. Fig. 3 is a cross-section of said generator on line $z z$ of Fig. 2, and Fig. 4 is an elevation of the vessel or water-section which I suspend within the fire-pot and which forms the principal feature of my invention.

35 The letter a in the drawings denotes the outer jacket or shell of the generator, b the inner wall, and c an intermediate wall or shell, the three shells being substantially concentric with each other and forming three separate 40 chambers, the central one being the fire-pot of the generator. The space between walls b and c contains the water to be heated, and the space between walls c and a provides a hot-air jacket, as hereinafter described. A 45 grate d and ash-pit e , both of ordinary construction, are provided, and preferably a dome f is connected with the top of the boiler-section by a series of pipes g , above which and leading outward from said dome is a corresponding 50 series of pipes h , to which may be connected service-pipes leading to radiators located at distant points. The outer jacket

a is cast with a flange or collar i to receive a draft-pipe leading to the chimney.

Within the fire-pot is a vessel k , preferably 55 of globular form, as shown, having projecting from both the upper and lower portions thereof a series of hollow arms k' , that connect the interior of the said globular vessel with the water-space between the walls b and c . The 60 arms k are cast integral with the wall b , and it will be understood that the water between the walls b and c and surrounding the fire-pot and combustion-chamber may freely pass 65 through the globular vessel k , and thus circulate in small volume through and around the fire. In practice the superheated water in vessel k tends to rise, and is followed and replaced by the slightly-cooler water between the walls b and c , which in turn is superheated and passes upward, only to be followed by other water from outside the fire-pot. This results in a constantly-circulating 70 body of hot water, which may be drawn from pipes h as required.

75 The peculiar arrangement of arms k' relative to the globular vessel k and the adjacent water-jacket around the fire-pot should be noted. The upper series of arms k' reach upward at an angle of perhaps thirty degrees 80 and afford an easy and unobstructed outlet for the superheated water, which naturally rises, while the lower series of arms extend downward to the lower portion of the water-jacket, where the cooler portions of the water 85 are wont to settle. The cooler portions of the water (needing most the influence of the fire-pot and combustion-chamber) are thus naturally drawn upward into the globular vessel k , where they are immediately superheated and passed onto the dome to be used 90 when necessary. I have indicated by an arrow at the upper end of the fire-pot the direction followed by the smoke and other products of combustion under a direct draft; 95 but, when desired, a suitable damper in the smoke-pipe may be closed, or partially closed, in which case the hot air is checked and thrown back into the annular space between walls c and a , thus surrounding the water-jacket and assisting materially in heating the 100 water therein contained.

The generator, as above described, is extremely simple in construction, may be eco-

nomically run, and requires no special training or experience on the part of the operator. My improved generator has also the advantage of being portable.

5 Having thus described my invention, I claim—

1. In combination in a generator of the class referred to, outer, inner, and intermediate shells providing a central fire-pot, a water-jacket surrounding said fire-pot, and a hot-air jacket surrounding said water-jacket, all as set forth, and a superheating-chamber suspended within said fire-pot and connected by hollow arms with said water-jacket, said 10 arms being cast integral with the water-jacket, as and for the purpose specified.
- 15

2. In combination in a generator of the class referred to, outer, inner, and intermediate shells providing a fire-pot, water-jacket, and hot-air jacket, as set forth, a dome connected 20 by water-legs with said water-jacket, service-pipe connections leading outward from the said dome, and a superheating-chamber suspended within the said fire-pot by hollow arms cast integral with the said water-jacket, 25 all being substantially as and for the objects specified.

WERTER C. HIGGINS.
